UNITED STATES PATENT OFFICE.

WILLIAM I. BETTIS, OF LOS ANGELES, CALIFORNIA.

AIR LIFT.

Application filed January 25, 1923. Serial No. 614,760.

To all whom it may concern:

Be it known that I, WILLIAM I. BETTIS, a citizen of the United States, residing at Los Angeles, in the county of Los Angeles and State of California, have invented new and useful Improvements in Air Lifts, of which the following is a specification.

This invention relates to water lifting apparatus and more particularly to so-called "air lifts".

In the ordinary systems of lifting water by the discharge of jets of air thereinto at a suitable depth, the air is discharged substantially continuously in a number of streams with the result that the air of each stream tends to coalesce or merge into a large bubble.

It is the broad object of my present invention to provide a method for the air lifting of water wherein a large number of jets of air are each intermittently discharged into the column of water. In other words, the method consists of intermittently breaking discharging streams of water into a great number of small discharged volumes so that each of the discharged volumes of air may remain independent of the other and thus materially reduce the tendency of the air to ascend in a comparatively large bubble, as is common in air lift apparatus in which the air is discharged through a jet outlet which is continuously open.

Another object of the invention is to provide an apparatus for discharging a considerable number of jets intermittently broken into short periods of discharge.

A further object is to provide a mechanism including a fixed valve member and a relatively movable valve member where by the air is discharged by the intermittent opening and closing of outlets in the valve. Another object is to provide an air discharge apparatus for air lifts wherein means are utilized that is adapted to be operated by the flowing air discharge from the apparatus for actuating the intermittently discharging valve means.

Other objects and advantages will be made manifest in the following specification of an embodiment of the invention illustrated in the accompanying drawings, wherein—

Figure 1 is a vertical section and partial side elevation of a form of the apparatus.

Fig. 2 is a plan of a form of air dis-

charge nozzle for impinging streams of air upon a contiguous fan or driving wheel.

Fig. 3 is a plan of a form of rotary valve member.

The present invention is disclosed as for use in an air lift wherein a column of water W is contained in a well casing or other structure 2, downwardly into which is extended an air pipe 3 leading to the upper portion of the well to be supplied with compressed air from a suitable source.

Upon the lower end of the air pipe 3 there is secured, in the present form of the invention, a foot piece comprising an air receiver or chamber 4 having a bonnet 5 which is shown as provided with a considerable number of preferably small discharged apertures 6. This discharge bonnet is secured as by a hub 7 to the lower end of the air pipe 3, and within the hub 7 there is provided a plate 8 having a number of obliquely arranged air passages 9 which are shown as arranged in a circle and in which circle the passages are inclined obliquely symmetrically so as to discharge jets 20 of air with impelling action upon the contiguous blades of a water wheel or driver 10 which runs close under the plate 9 and is secured on an upright shaft or spindle 11. The upper end of the spindle is supported, as for instance, in the lower face of the plate 8, and in the lower end is supported in antifriction bearings 12 in the bottom of the air receiver 4.

The fixed discharge valve member or bonnet 6, as shown, is of circular form and extends well beyond the pipe 3, and leaves an ample clearance space between the inner surface of the water casing 2 and its own perimeter for the upward flow of water.

Operatively fitting upwardly against the lower inner face of the discharge bonnet 6 is a rotary valve member 14 which is provided with discharge apertures 15 adapted to be registered during the rotation of the valve member 14 with the numerous discharge apertures 6 of the outlet bonnet 5. The distribution of the respective apertures in the two valve members is such as to most efficiently diffuse and disseminate the discharging bubbles of air in a most thorough manner generally throughout the transverse section of the column of water horizontally in a plane just above the discharge valve.

In the present case the valve member 14 is operated by the shaft 11 to which it is secured; in this instance the valve member 14 being formed as a part of the driving wheel 10.

From the above it will be seen that upon relative movement of the two valve members 6 and 14, small jets of air will be intermittently discharged from the chamber 4 upwardly into the column of water in the water casing 2, and by reason of the intermittent discharge numerable independent bubbles will be caused to form in and rise in and with the column of water. The formation of these bubbles by interruption of the discharging streams materially increases the efficiency of the air lift apparatus by the elimination of large coalesced volumes of air, which is common in apparatus discharging continuous streams of jets of air into the water column.

It is to be clearly understood that any suitable form of valve and any suitable form of operating mechanism may be employed, the gist of the present invention residing in a method and in an apparatus for discharging relatively small independent jets or bubbles of air into a column of water and which may be accomplished by the rapid opening and closing of valve means controlling the passage of air from a source of supply into the water.

It is to be understood that while reference is made in this specification to water as the material to be acted upon, the apparatus may be equally as serviceable with various other liquids and especially for use in oil wells.

Further embodiments, modifications and variations may be resorted to within the spirit of the invention as here claimed.

What is claimed is:

1. Air lift apparatus comprising an automatic valvular means for intermittently discharging small independent volumes of air into the liquid to be lifted.

2. An air lift apparatus comprising submersible valvular means having a distributing head whereby air is dischargeable in isolated sets in intermittent periods into liquid to be elevated.

3. An air lift apparatus comprising means whereby air bubbles are discharged intermittently into the water to be acted upon, said means including valve elements operable to discharge air in intermittent jets.

4. An air lift apparatus comprising means whereby air bubbles are discharged intermittently into the water to be acted upon, said means including valve elements operable to discharge air in numerous intermittent jets.

5. An air lift apparatus comprising means whereby air bubbles are discharged intermittently into the water to be acted upon, said means including valve elements operable to discharge air concurrently in intermittent jets.

6. Air lift apparatus comprising means whereby very minute air bubbles are discharged intermittently into the water to be acted upon, said means including valve elements operable to discharge air in intermittent jets.

7. Air lift apparatus comprising means whereby very minute air bubbles are discharged intermittently into the water to be acted upon, said means including valve elements operable to discharge air concurrently in numerous intermittent jets.

8. A foot piece for an air lift, comprising a stationary valve member having an orifice and a movable valve member having an orifice, the orifice in said movable member passing transversely across the orifice in said stationary member.

9. A foot piece for an air lift, comprising an outer valve member having an orifice and an inner valve member having an orifice, said orifices of the inner and outer members being adapted to move across each other.

10. A foot piece for an air lift, comprising an outer stationary valve member having an orifice, and an inner rotary valve member having an orifice, and means for rotating said rotary valve member to move the orifice of the rotary valve member across the orifice of the stationary member.

11. A foot piece for an air lift, comprising a stationary valve member having a series of orifices, and a movable valve member having a series of orifices, the orifices of said movable valve member being adapted to pass transversely across the orifices of the stationary valve member, and means for rotating said movable valve member across the face of the stationary valve member.

In testimony whereof I have signed my name to this specification.

WILLIAM I. BETTIS
